Patented Feb. 24, 1920.

FIG. 3.

FIG. 4.

INVENTOR
Henry A. Carson

BY
George W. Hinton
ATTORNEY

UNITED STATES PATENT OFFICE.

HENRY A. CARSON, OF ST. JOSEPH, MISSOURI.

INTERNAL-COMBUSTION ENGINE.

1,331,695.

Specification of Letters Patent. Patented Feb. 24, 1920.

Application filed October 29, 1917. Serial No. 199,035.

To all whom it may concern:

Be it known that I, HENRY A. CARSON, a citizen of the United States, residing at St. Joseph, in the county of Buchanan and State 5 of Missouri, have invented certain new and useful Improvements in Internal-Combustion Engines, of which the following is a specification, reference being had therein to the accompanying drawing.

10 My invention relates to improvements in internal combustion engines, and the objects of my improvements are, first: to provide a simple, substantial and durable engine, of this class, which shall be of the two cycle 15 type, second: to so construct and arrange the parts of an internal combustion engine, that practically all of the products of combustion shall be expelled therefrom at each and every return stroke of the pistons, third: to so construct the engine, that the gaseous fuel inducted therein shall not be compressed before ignition of the fuel, fourth; to provide anti-concussion means whereby abrupt stopping of the outward movement of the 20 intake pistons is prevented.

I attain these objects by the mechanism illustrated in the accompanying drawings, in which:—

Figure 1 is a vertical section of the engine, 30 on the line Y Y, seen in Fig. 2, looking toward the fly wheel. Fig. 2 is a horizontal section, on the line X X, seen in Fig. 1, looking downward. Fig. 3 is an enlarged side view, in detail, of the exhaust cam. 35 Fig. 4 is a transverse section, in detail, of the crank case, on the line Z Z, seen in Fig. 1, looking toward the right.

Referring to Fig. 1, cylinders 1 and 2, have base blocks 3 and 4, respectively formed 40 therewith. Said blocks are adapted to be secured on an engine base, (not shown,) by their respective stud bolts and nuts 3' and 4'.

Piston 5 is connected with crank shaft 8, by rod 9 and crank 10. Said crank shaft is 45 extended through the crank case 11, and is rotatably mounted with said crank in said case. Said crank case is formed integrally with the adjacent ends of cylinders 1 and 2. Piston 5 and piston 6 are slidably mounted 50 in said cylinders, respectively. Said pistons are rigidly connected by connectors 7, which are formed integrally therewith.

Since said cylinders, their respective pistons, and their hereinafter described respective coacting parts, form two sets of mechanisms, which are the same in construction

and operation, for alternate action, but one set is described.

Intake cylinder 12 is secured on the outer end of cylinder 1, in alinement therewith. Said intake cylinder is provided with spark plug 13, which is adapted to be connected with an electric igniting system, and since said system may be any one of the various igniting systems now in use, and forms no 60 65 part of my invention, the same is neither shown nor described.

Said intake cylinder is provided with fuel intake 14, (see Fig. 1,) which latter is provided with valve 15, which valve is 70 actuated to close said fuel intake, by the spring 16.

Intake cylinder 12 is also provided with the exhaust outlet 17, (see Fig. 2,) which outlet is provided with valve 18.

Said valve is provided with stem 18', which is actuated by spring 19 for closing said valve. Cam 20 is secured on crank shaft 8, and is adapted by rotation thereof, past the inner end of said stem, to move the 80 latter and thereby open said valve.

Intake piston 21 is slidably mounted in intake cylinder 12, and is actuated to move outward, by piston springs 22.

The outer end of said piston is adapted to 85 inclose and compress a certain amount of air, in cushion chamber 12', for gradually stopping the outward movement of said piston.

Chamber 12' is provided with the vent 90 cock 31, by which exit of air from said chamber is regulated.

Intake piston 21 is moved inward by cam 23, which is rotated against friction roll 24; said roll being rotatably mounted between 95 the outer ends of piston rods 25, the inner ends of which are secured in piston 21.

Cam 23 is secured on the central portion of cam shaft 26, which latter is rotatably mounted in the outer ends of bearing brackets 27, which are secured on the outer end of intake cylinder 12. Sprocket wheel 28 is secured on one end of said cam shaft, and is connected by sprocket chain 29, with sprocket wheel 30, which is secured on crank 100 shaft 8.

In operation, with the parts in the position seen in Fig. 1, fly wheel 32 is manually rotated clockwise, thereby rotating shaft 8 and the therewith connected cam 23. When 110 the end of said cam passes friction roll 24, piston springs 22 move piston 21 outward.

- This movement of said intake piston is gradually stopped by a cushion of air, which is formed in cushion chamber 12', and escapes therefrom, through vent cock 31. 5 When said piston is thus moved, it produces a partial vacuum in cylinder 12, which inducts a charge of explosive gaseous fuel into said cylinder. Said fuel is inducted from an unshown source of supply, 10 through fuel intake 14, past valve 15, overcoming spring 16, opening said valve, and thence into cylinder 12; after which said valve is closed by the last mentioned spring. It will be understood, that the action of 15 springs 22, moves said intake piston almost instantly, thereby filling cylinder 12 with said fuel, before piston 5 has moved an appreciable distance. At this juncture, said charge of fuel is ignited at spark plug 13, by 20 the previously mentioned igniting system.

The energy of the ignited charge drives piston 5, toward crank shaft 8, which, by its rod and crank connections, rotates said shaft clockwise, until said piston has reached the 25 end of its stroke, and is in a position, similar to that of piston 6.

During the previously described operations, the last mentioned piston and its coacting intake piston, together with their 30 driving mechanisms, are moved from the position shown, to a position similar to the shown position of piston 5 and its coacting parts.

Fly wheel 32 is now rotated by its own 35 inertia, which rotates shaft 8 and its connected parts, thereby moving piston 6 and its coacting set of parts, in the same manner as the previously described movements of piston 5 and its coacting parts. This 40 movement similarly inducts a charge of fuel between piston 6 and its intake piston. This charge is similarly ignited, the energy from which, drives piston 6 toward shaft 8, until all of the parts of the engine have thereby 45 been moved, from their described positions, to the positions shown.

While piston 5 is thus being moved to-

ward its intake piston 21, cam 23 moves the last mentioned piston inward, until said pistons are in the position shown, as previously 50 stated.

During the first half of this piston movement, exhaust cam 20 is rotated past the end of valve stem 18', (see Figs. 2 and 3), thereby opening valve 18. During the last half 55 of said movement said valve is closed by action of spring 19. At this juncture pistons 5 and 21, having reached the position shown, have expelled, practically all of the products of combustion, from cylinders 1 60 and 12, through exhaust outlet 17 and the thus opened valve 18.

The inertia of fly wheel 32 continues rotating shaft 8, and the described operations are repeated.

It will be understood that the previously mentioned gaseous fuel is not compressed in the described engine, and that the same may be fed through fuel intake 14, (see Fig. 1), at one atmosphere, or at any higher pressure that may be desired, which higher pressure must not be sufficient to normally overcome spring 16, by its pressure against valve 15.

Having fully described my invention, 75 what I claim as new, and desire to secure by Letters Patent, is:—

In an internal combustion engine provided with an intake cylinder and an intake piston in said cylinder; the combination with said piston, of a cam for moving said piston inward and springs for moving said piston outward; and a vent cock in the outer end of said cylinder whereby exit of air from said cylinder is regulated, for pneumatically cushioning said piston against abrupt action of said springs.

In testimony whereof I affix my signature in the presence of two witnesses.

HENRY A. CARSON.
